UNITED STATES PATENT OFFICE.

WILLIAM BLOCK, OF CHICAGO, ILLINOIS.

DESIGN FOR A FINIAL FOR LAMPS.

Application filed December 7, 1925. Serial No. 15,675. Term of patent 3½ years.

To all whom it may concern:

Be it known that I, WILLIAM BLOCK, a citizen of the United States, residing at Chicago, in the county of Cook and State of Illinois, have invented a new, original, and ornamental Design for a Finial for Lamps, of which the following is a specification, reference being had to the accompanying drawing, forming part thereof.

The figure is a side elevational view of a finial showing my new design.

I claim:

The ornamental design for a finial for lamps, as shown.

WILLIAM BLOCK.
